Atty.

UNITED STATES PATENT OFFICE.

JOHN F. MACKAY, OF BORDENTOWN, NEW JERSEY.

HOVER OR BROODER.

Specification of Letters Patent. Patented Feb. 19, 1918.

1,256,711.

Application filed January 17, 1916, Serial No. 72,442. Renewed July 19, 1917. Serial No. 181,663.

To all whom it may concern:

Be it known that I, JOHN F. MACKAY, a citizen of the United States, residing at Bordentown, in the county of Burlington and State of New Jersey, have invented certain new and useful Improvements in Hovers or Brooders, of which the following is a specification, reference being had therein to the accompanying drawing.

10 My invention refers to a hover device for use on poultry farms for covering and protecting the young chicks. The object of the invention is to provide means whereby the chicks or birds may be kept in a warm compartment free from drafts, and in a compartment which will be properly lighted so that the chicks will distribute themselves throughout the area thereof without huddling together in the corners. The invention, therefore, comprises various details of combination and arrangement to the end that the best results may be attained with such a device, all substantially as will be hereinafter described and then more fully 25 pointed out in the claims.

In the accompanying drawing illustrating my invention:

Figure 1 is a vertical section of my improved hover device for use in the raising of 30 chickens.

Fig. 2 is a top plan view of the same with a portion broken away.

Similar characters of reference designate corresponding parts throughout the different figures of the drawing.

In connection with my present improved brooder, I find it convenient to employ gas resulting from the volatilization of kerosene, gasolene, or some other hydrocarbon or other oil, the same being supplied through a pipe 4 which leads to a burner 5, the pipe being provided with a valve 6 to control the supply of oil. The burner 5, when the gas is ignited, gives forth a large amount of heat 45 which is amply sufficient to warm the interior of the hover or hood 1, sufficiently to provide a chamber of proper temperature for taking care of the chicks. A gas burner of this kind is found to possess many advantages over a stove consuming wood and coal as fuel, or a lamp or oil heater, although with regard to certain features of the hover it is probable that they can be used in combination with other heaters than a gas 50 burner, and consequently a rearrangement of the parts can easily be made to suit dif-

ferent conditions, but I lay considerable stress upon the easy and simple application of a gas burner for this purpose, which burner consumes the gas resulting from the atomizing of kerosene, gasolene, and the like.

The hover 1 is a conical hood having an opening 7 at the top which is closed at times by the conical cover 8, which forms the apex 65 of the conical form of the hover or hood. This hood 1 is supported upon a horizontal platform 3, which is in turn supported on a cylindrical standard 2 which surrounds the burner and the pipe leading to the 70 burner. The platform 3 is provided with an encircling flange 9 of greater or less size, which may, if desired, be in the form of a curtain, or may carry a curtain, and at one point adjacent to the flange 9 and beneath 75 the platform 3 I suspend a thermometer 10 from the platform so as to indicate the temperature beneath it.

11, 11 denote draft tubes which are attached to the hood 1 near the upper end 80 thereof and which lead downwardly through the interior of the space within the hood 1 into the space within the cylindrical standard 2, and which carry outside air downwardly into the interior of cylinder 2 as 85 shown by the arrows. There may be any number of these draft tubes 11, while in the present example of the invention, I have shown only a couple.

Also beneath the platform 3 is a thermostat 12 which in expanding operates a lever 13 pivoted to a link 14 which passes upward through a tube 15 supported on the hover 1, said rod 14 being attached to a lever 16, which carries the cover 8 at the top opening 95 of the hood 1, and is also provided with a counterbalancing weight 17. As the thermostat 12 expands, the rod 14 draws downwardly on the lever 16 and lifts the cover 8 off the hood so that the hot air can pass out, 100 it being evident that the temperature at this time is higher than it should be and that a certain amount of hot air should be disposed of. The tube 15 which is supported on the hover 1 is preferably arranged so as to carry 105 the main frame 18 of the thermostat 12, said tube 15 being fastened to the frame 18 by means of the set screw 19 which permits the parts 15 and 18 to be connected together or detached from each other. Moreover the 110 tube 15 is connected to a frame 20 mounted on the top of the hood 1 and having ears or

jaws 21 which support the fulcrum for the lever 16 that carries the cover 8. These parts may be modified within considerable limits if desired. The hood 1 is also provided with an opening 22 serving as a peep hole for permitting inspection of the burner 5 and the interior of the hood 1. The hood 1 may be lifted off the cylinder 2 so as to permit access to the burner 5 and the interior 10 of the hood whenever desired by the use of the cables 23 and 24 running over the pulleys 25 and 26 and attached to the hood at the point 27 and 28 as shown in Fig. 1. Furthermore, it will be noted that the cylinder 2 is provided with a door 29 covering an opening 30 which permits access to be had to the valve 6, as also to the interior of the cylinder 2, and in this way the gas can be turned on or off and repairs made to the interior of the 20 device.

In the use of a hover of this kind the little chicks or birds sometimes have a tendency to flock toward the outer edges where there are cold drafts and where the chicks would 25 not be as favorably situated, but might be injured by the drafts and other untoward influences, and, hence, I provide the platform 3 with a number of lights, say for example, four, consisting of isinglass or 30 transparent plates 31 covering openings 32 in the platform 3. These transparent plates allow the light to shine through sufficiently to attract the attention of the chicks. Hence the chicks do not collect at the outer edges 35 of the hover where they are injured by the cold drafts, but run freely about in the entire space around the cylinder 2 and beneath the platform 3 and the flange 9.

Many changes may be made in the precise 40 construction and combination of the various parts; therefore, I do not wish to be restricted to what I have delineated and described, but claim the liberty of making such modifications as are required in practice.

Having thus described my invention, what 45 I claim as new and desire to secure by Letters Patent, is:

1. In a hover or brooder, the combination 50 of an upright hollow support, heating means within the same, a horizontal platform resting removably on said upright at a substantial distance above the surface on which the upright rests, said platform being provided with an encircling flange around its periphery which forms a part of the wall of the

brooder chamber, a conical hood secured at its lower periphery to the outer edge of the platform and having an opening at the apex of the cone, said hood being provided with vertical air pipes extending downwardly 60 from the top into the upright support alongside of the heating means, a thermostat appliance under the platform and between the upright and the outer encircling flange, and a valve at the top opening of the hood, together with connections between the thermostat and said valve whereby the thermostat actuates the valve as the temperature of the brooder chamber varies.

2. The combination of an upright cylinder, a platform resting loosely thereon and having a central opening corresponding to the upper end of the cylinder and having also an encircling flange at its outer periphery, a conical hood secured to the platform 75 at its outer edge and provided with a central opening at its apex and with parallel vertical tubes extending downwardly into the lower cylinder from a point contiguous to the top central opening, a conical cover for 80 the latter opening, a thermostat supported below the platform and inside of the encircling flange, lever connections between said thermostat and the conical cover, and heating means within the cylinder and hood, and 85 transparent means at various points in the platform for allowing the light over the platform to illuminate the space below it wherein the chicks move about.

3. The combination of an upright hollow 90 member forming a support and having a door, heating means therein, a platform resting loosely upon the top of said supporting member and provided with a series of transparent plates to enable a passage of light to 95 the chicks and having also an encircling flange, a conical hood secured to the outer edge of the platform and having a central top opening, and means for admitting air from the top of the hood into the chamber 100 within the same, a conical cover for said top opening, a temperature control device which seats and unseats said cover as the temperature varies, means for lifting the hood and platform as a unit above lower support to 105 allow entrance into the latter, all substantially as described.

In testimony whereof I affix my signature.

JOHN F. MACKAY.
